A. A. BACKHAUS,
METHOD OF PRODUCING CATALYZERS.
APPLICATION FILED JUNE 15, 1918.

1,375,345.

Patented Apr. 19, 1921.

Arthur A. Backhaus,
Inventor
By his Attorney
Freidle, Wright & Small

UNITED STATES PATENT OFFICE.

ARTHUR A. BACKHAUS, OF BALTIMORE, MARYLAND, ASSIGNOR TO U. S. INDUSTRIAL
ALCOHOL CO., A CORPORATION OF WEST VIRGINIA.

METHOD OF PRODUCING CATALYZERS.

1,375,345.

Specification of Letters Patent. Patented Apr. 19, 1921.

Application filed June 15, 1918. Serial No. 240,223.

To all whom it may concern:

Be it known that I, ARTHUR A. BACKHAUS, of Baltimore, in the State of Maryland, have invented a certain new and useful Improvement in Methods of Producing Catalyzers, and do hereby declare that the following is a full, clear, and exact description thereof.

My invention relates particularly to a process of producing catalyzers which are used in the production of aldehydes.

The object of my invention is to provide a process by which catalyzers of the above type may be advantageously made and by which efficient catalyzers may be obtained to bring about the production of aldehydes, as for example, acetaldehyde, by passing alcohol over a catalyzer of this character while heated.

Another object of my invention is to provide a process of producing catalyzers containing copper to be used for the production of aldehydes in this way.

Further objects of my invention will appear from the detailed description thereof contained hereinafter.

While my invention is capable of being carried out in many different ways, I shall describe hereinafter only one way of carrying out the same, and shall show only one form of apparatus used in connection with the same in the accompanying drawing, in which—

The figure is a vertical section of a catalyzer made in accordance with my invention.

In carrying out my process, I fill a tube 1 with a large number of permeable and substantially parallel disks 2, which may be of copper, nickel, chromium or iron gauze, and which may be contiguous with one another or separated by rings 3, as desired.

The metal is a very good conductor of heat, and in this way the reaction temperature may be readily carried to all parts of the catalyzer tube 1, with which the disks are shown as contacting.

In order to make the gauze disks 2 active, so as to bring about the change from alcohol to acetaldehyde, the surfaces of the disks 2 are, in the present embodiment of my invention, corroded by passing a current of air and acetic acid vapors through an inlet tube 4 at one end of the catalyzer tube and out through a tube 5 at the other end of said

tube. Other methods for the formation of 55 the acetate *in situ* may be employed.

After the metal in the gauze disks 2 has been corroded by the formation of the acetate, the latter is partially decomposed into the oxid by heating the copper catalyst tube 1 to a temperature of 300° C. or higher in any suitable manner and then reducing the oxid *in situ* by passing a current of hydrogen into the catalyzer tube 1 and heating the same to a temperature of 300° C. 65

In this way a very finely divided deposit of the metal is carried by the meshes of the metal disks 2, and thereafter, when a current of vapors of an alcohol, such for example as ethyl alcohol, is passed through 70 the tube 1 while heated to a temperature of approximately 300° C., the finely divided metal causes the alcohol to be broken down into acetaldehyde and hydrogen, which may be conveyed away and separated in any 75 suitable manner.

During the formation of the acetaldehyde, the heating of the catalyzer tube 1 may be very effectively carried out by the external application of heat, which is readily conveyed to all portions of the catalytic material by reason of the fact that the latter is carried upon the disks of metal gauze 2, which form very effective conductors of heat. In this way the acetaldehyde will be 85 very uniformly formed from the alcohol vapors.

While I have described my invention above in detail, I wish it to be understood that many changes may be made therein 90 without departing from the spirit of my invention.

I claim:

1. The process which comprises producing a catalyst by treating a copper body to 95 form a copper salt thereon and then depositing finely divided reduced copper from said salt upon the same.

2. The process which comprises producing a catalyst by treating a body of copper 100 gauze to form a copper salt thereon, the treatment being effected by acetic acid vapors and air, and then depositing finely divided reduced copper from said salt upon the same.

3. The process which comprises producing a catalyst by treating a copper body to 105 form a copper salt thereon, the treatment

being effected by acetic acid vapors and air, and then depositing finely divided reduced copper from said salt upon the same by igniting to form an oxid from said salt and 5 reducing the oxid with a current of hydrogen.

4. The process which comprises producing a catalyst by introducing a plurality of disks of copper gauze into a copper tube, 10 treating said disks to form a copper salt thereon, and then depositing finely divided reduced copper from said salt upon the same.

5. The process which comprises producing a catalyst by introducing a plurality of disks of copper gauze into a copper tube, 15 treating said disks to form a copper salt thereon, the treatment being effected by acetic acid vapors and air, and then depositing finely divided reduced copper from said salt upon the same.

6. The process which comprises producing a catalyst by introducing a plurality of disks of copper gauze into a copper tube, 20 treating said disks to form a copper salt thereon, the treatment being effected by acetic acid vapors and air, and then depositing finely divided reduced copper from said salt upon the same by igniting to form an 25 oxid from said salt and reducing the oxid with a current of hydrogen.

7. The process which comprises producing a catalyst by treating a body of copper gauze to form a copper salt thereon and 30 then depositing the finely divided reduced metal from said salt upon the same.

8. The process which comprises producing a catalyst by treating a body of metal gauze to form a salt thereon, the treatment being effected by acetic acid vapors and air, and then depositing the finely divided reduced metal from said salt upon the same. 35

9. The process which comprises producing a catalyst by treating a metal body to 40 form a salt thereon, the treatment being effected by acetic acid vapors and air, and then depositing the finely divided reduced

metal from said salt upon the same by igniting to form an oxid from said salt and reducing the oxid with a current of hydrogen. 50

10. The process which comprises producing a catalyst by introducing a plurality of disks of copper gauze into a copper tube, 55 treating said disks to form a copper salt thereon, and then depositing the finely divided reduced metal from said salt upon the same.

11. The process which comprises producing a catalyst by introducing a plurality of disks of metal gauze into a tube, treating 60 said disks to form a salt thereon, the treatment being effected by acetic acid vapors and air, and then depositing the finely divided reduced metal from said salt upon the 65 same.

12. The process which comprises producing a catalyst by introducing a plurality of disks of copper gauze into a copper tube, 70 treating said disks to form a copper salt thereon, the treatment being effected by acetic acid vapors and air, and then depositing the finely divided reduced metal from said salt upon the same by igniting to form an oxid from said salt and reducing the 75 oxid with a current of hydrogen.

13. The process which comprises assembling, within a metallic tube and in heat-conductive relationship therewith, a large 80 number of permeable disks made of a metal susceptible of attack by acetic acid in the presence of oxygen, passing acetic acid and an oxidizing gas through said tube to react with the surface material thereof, partially decomposing *in situ* the resulting acetate, 85 and thereafter reducing *in situ* the product of such partial decomposition, to form a catalyst.

In testimony that I claim the foregoing I have hereunto set my hand.

ARTHUR A. BACKHAUS.
